SEPARATOR FOR COINS

Richard E. Perkins, Holliston, Mass., assignor to Electronic Coin Processing Corporation, New York, N.Y., a corporation of New York

Filed Apr. 13, 1961, Ser. No. 102,744

3 Claims. (Cl. 133—3)

This invention relates to coin handling machines and more particularly comprises a device for sorting coins by size. It constitutes an improvement over the coin sorting device shown in an application of White, Serial No. 49,909, filed August 16, 1960, and entitled Mutilated Coin Separator. This invention has numerous applications, although particularly suited for use in combination with other devices which determine the authenticity of coins by inspecting other than their size.

In coin handling equipment of virtually all varieties, it is advantageous to sort coins of each denomination by size to remove all coins which are worn and/or mutilated from coils in good condition. For example, even in coin handling machines of large capacity, coins are normally fed one at a time in very rapid succession through successive stages and abnormally shaped or sized coins may jam or otherwise cause the machine to function improperly. Thus, by separating the abnormally sized and mutilated coins from those coins in good condition such difficulties may be avoided.

To separate worn and/or mutilated coins from normal coins, I provide a closed box, preferably square in cross section, which is rotated about an axis coincident with the centers of the ends of the box. Extending away from the inner surface of the trailing edge of each side wall of the box are a plurality of slots dimensioned to very close tolerances. The box is intended to handle coins of a single denomination. The slots have width and height dimensions but a few thousandths of an inch more than the diameter and thickness of normal unmutilated coins of that denomination and may be of substantial length.

As the box rotates about the described axis, the coins fed to the box slide down the flat walls toward the slots formed at the trailing edges. The coins which are of a proper size would, in the absence of other structure, slide freely through the slots and be accepted as unmutilated coins of the proper size for the denomination under test. This is precisely what takes place in the coin separator forming the subject matter of the White application, supra.

As an additional feature and improvement, my coin separator includes chambers formed just beyond the ends of the slots, which receive each of the coins that escapes from the box through the slots. The chamber is provided with a circular opening of a diameter a few thousandths of an inch greater than the normal diameter of unmutilated coins of the denomination under test. Thus, the coins are subjected to an additional test when the improvement disclosed herein is incorporated as a part of the coin separator; namely, if the diameter of a coin measured in any direction exceeds the normal diameter of the coin of the denomination under test, it will not fall through the circular slot from the chamber but rather will be retained in it. While such a coin may pass through the slot formed in the box wall so long as the enlarged diameter does not align itself with the slot, the coin may not pass through the circular opening.

These and other objects and features of my invention will be better understood and appreciated from the following detailed description of one embodiment thereof, selected for purposes of illustration and shown in the accompanying drawing, in which:

2

FIG. 1 is a side view of a coin separator constructed in accordance with my invention;

FIG. 2 is a perspective view of a major portion of the coin separator shown in FIG. 1; and

FIG. 3 is a cross sectional view taken along the corresponding section line in FIG. 2.

The coin separating mechanism shown in FIG. 1 includes in its general organization a box 10 supported for rotation by shaft 12 about an axis defined by the shaft bearing 14. The shaft 12 is rotated in the direction of arrow 16 by motor 18 through belt 20 and pulleys 22 and 24. Pulley 22 is shown in FIG. 1 to be carried on the shaft of motor 18 while pulley 24 is shown mounted on the supporting shaft 12 which supports the box.

The shaft 12 extends through the circular opening 26 formed in end wall 28 of box 10 and does not interfere with the introduction of coins into the box through that opening. The shaft 12 supports the box 10 by means of a spider 30 suggested diagrammatically by broken lines in FIG. 1 and by engaging the other end wall 32 of the box which is imperforate except for the small opening through which the shaft 12 actually passes. Thus, the shaft 12 firmly supports the box 10 and causes the box to rotate with it.

The box 10 is generally defined by end walls 28 and 32 and side walls 40, 42, 44 and 46. Each of the side walls extends on one side a considerable distance beyond the edge of the adjacent side wall to which it is secured and supports a block on the portion beyond the adjacent side wall. Thus, as is clearly shown in FIGS. 2 and 3, wall 40 supports block 48, wall 42 supports block 50, wall 44 supports block 52, and wall 46 supports block 54.

The blocks are supported on the extended side of each side wall and engage the edge of the adjacent side wall in each instance. The inner edge of each of the side walls defines with the adjacent wall a continuous plane extending up from the supporting side wall. Thus, in FIGS. 2 and 3, it will be noted that the inner edge 56 of block 52 forms a continuation of the inner surface of the wall 46 and they together define a plane extending upwardly from the surface of wall 44. A similar arrangement is shown on each of the other sides.

The blocks are each provided with a plurality of parallel slots 60 formed in the face lying on the supporting wall, which slots have a width w but a few thousandths of an inch greater than the diameter of the normal coins of the denomination to be sorted. The height h of each slot 60 is a few thousandths of an inch greater than the thickness of the denomination of coins to be sorted. Thus, the slots have width w and height h dimensions substantially equal to the diameter and thickness of the normal coins but just large enough to permit them to slide into the slots in the absence of any mutilation.

The slots 60 terminate in or register with circular openings 62 extending from the upper or outer surface 64 of the blocks so that the slots 60 and circular openings 62 together define passages extending through the whole thickness of the blocks. When the blocks are disposed on the planes in the manner shown in FIG. 3, each slot 60 and circular opening 62 cooperate to form a chamber immediately outside the box 10 into which coins may slide when of normal size. Further, the circular openings 62 form an exit for coins from the chamber after they have left the box.

In the foregoing description the width and height of the slots 60 have been described as testing the diameters and thicknesses of the coins fed to the box 10. In addition, the slot 60 and the opening 62 test for coin mutilation. The length through which coins must pass between the point of entry into one slot 60 and the position wherein it is aligned with circular openings 62 is substantial. As

a result, if a coin entering the slot 60 is even slightly bowed, it will lodge in the slot 60 rather than pass through it to the base of the circular opening 62. The effective length of the passage as determined by minimum coin travel is at least equal to the coin diameter.

It will be recognized that if the passages 60 continued to the outer edge of the block 52 rather than stop short thereof, an unbowed coin not exceeding normal thickness and having a diameter measured in one direction not exceeding the width of the slot could pass out of the box if the coin aligned itself with one of the slots. Thus, referring to FIG. 3, the coin 66 could pass through the slot 60 (assuming the absence of circular opening 62) so long as the coin thickness did not exceed the height h of the slot 60 and the diameter of the coin as measured normal to the plane of the drawing did not exceed the width w of the slot. Thus, even though the diameter of the coin as measured in the plane of the paper exceeded the normal diameter of the coin, it could pass through the slot 60 out of the box if the slot 60 continued along the surface of wall 44. However, by closing the end of the slot 60, that is, by providing a stop at the end of the slot 60 formed by the outer portion of the block itself, and causing the coin to escape through the circular opening 62, the diameter of the coin 66 is tested in all directions and must conform in all directions to the diameter of the circular opening 62 in order that it can escape from the box.

Having described the details of my invention, I will now briefly describe its operation. In use, the motor 18 rotates the box 10 on the shaft 12 at approximately one revolution per second, and as the box rotates the particular denomination of coins for which the box is designed are fed to it through the opening 26 in the end wall 28. Referring to FIG. 3, assume that the box 10 is rotating in the direction of arrow 16 and a number of coins lie on the side wall 44 of the box. When the box 10 has rotated approximately 30 degrees from the position shown in FIG. 3, the coins disposed on the bottom wall 44 will slide toward the slots 60 in the block 52 formed adjacent the trailing edge of the wall 44. Those coins which in thickness do not exceed the height h of the slots 60 and whose diameters aligned longitudinally with the wall 44 do not exceed the width w of the slots, and those coins which are not bowed any substantial amount will enter the slots 60 and pass to the position suggested by coin 66'. Such coins will remain in the end of the chambers defined by the slots 60 and circular openings 62 until they are literally dumped from the chambers when each is inverted as suggested by the position of block 48. It will be noted in FIG. 3 that a coin 66" is shown falling from the block 48. Coins will drop from the box 48 or any of the other boxes through the openings 62 only if their diameter is uniform and within the dimensions dictated by the diameter of the openings.

In FIG. 1 it will be noted that a bin 70 is provided below the box 10 and is positioned to collect all coins which pass through the slots and openings. Such coins may be directed by the chute 72 to any desired location where additional tests may be performed on the coins to determine their authenticity. Oversized coins or mutilated coins will collect in the box 10 and periodically the operator may shut down the system to clear those coins from the box. If this is not done, the capacity of the box to sort coins may be impaired.

Having described my invention in detail, those skilled in the art will appreciate that numerous modifications may be made of the illustrated embodiment without departing from the spirit of my invention. Therefore, I do not intend to limit the breadth of my invention to the single embodiment illustrated and described. Rather, it is my intention that the breadth of this invention be determined by the appended claims and their equivalents.

What is claimed is:

1. In a coin sorter, walls defining a slot having width and height dimensions a few thousandths of an inch larger than the diameter and thickness of an unworn and unmutilated coin of the denomination to be sorted, means disposed at the end of the slot preventing coins from moving translationally beyond a selected point in the slot, a wall overlying the end of the slot, a circular opening formed in the wall in a plane parallel to the slot and having a diameter a few thousandths of an inch larger than the diameter of the unmutilated coin, and drive means connected to the sorter and periodically inverting the slot causing coins which fit within the slot to slide into the slot and drop out of the slot through the circular opening.

2. A coin sorter comprising walls defining a closed box square in cross section, means for rotating the box about an axis coincident with the center of the section, means defining slots extending upwardly from adjacent the trailing edges of each wall, said slots having a width and height substantially equal to the diameter and thickness of normal coins of the denomination to be sorted, additional walls defining coin chambers beyond the slots, said chambers having coin supporting surfaces forming continuations of the bottoms of the slots, and circular exit passages formed in the additional walls in a plane parallel to and above the supporting surfaces, said passages having a diameter just exceeding the diameter of normal coins of the denomination to be sorted whereby when each chamber is inverted as the box rotates normal coins in the chambers may fall out through the exit passages.

3. A coin sorter comprising walls defining a closed box, means for rotating the box, an inlet formed in the box for introducing coins into its interior, means defining slots extending upwardly from adjacent the trailing edges of each wall, said slots having a width and height substantially equal to the diameter and thickness of normal coins of the denomination to be sorted, additional walls defining coin chambers beyond the slots, said chambers having coin supporting surfaces forming continuations of the bottoms of the slots, and circular exit passages formed in the additional walls in a plane parallel to and above the supporting surfaces, said passages having a diameter just exceeding the diameter of normal coins of the denomination to be sorted whereby when each chamber is inverted as the box rotates normal coins in the chambers may fall out through the exit passages.
